DOOR BRACE AND GUIDE MECHANISM

Edward H. McCloud, Columbus, Ohio, assignor to
The Kinnear Manufacturing Company, Colum-
bus, Ohio, a corporation of Ohio

Application July 23, 1930. Serial No. 469,995

19 Claims. (Cl. 20—20)

This invention relates to door braces and guide mechanisms therefor, and has for its object the provision of means for bracing an overhead door and prevent its sagging during the time it is supported in an overhead condition, as well as in vertical position.

It is also an object of this invention to provide, in connection with a reenforcing bar, guide means adapted to support the door in the process of opening and closing and in an open condition.

It is a further object of this invention to provide, in connection with a door composed of sections, means for pivotally attaching one section to another, and provide in connection with said pivotal means, means for guiding the door in the process of opening and closing, and means for preventing the sagging or misformation during and because of its suspended condition overhead.

It is also an object of this invention to provide in connection with the hinges that connect the door sections, shafts which have on the ends thereof rollers engaging a supporting member. These rollers are supported on the shafts so that there is a limited amount of movement longitudinally of the shafts as well as around the shafts.

It is also an object of this invention to provide a transversely disposed reenforcing bar formed of sheet metal in the shape of an inverted U, with the open part thereof adjacent the door and with one end permanently attached adjacent one side of the door and the other end attached to the other side of the door in such a manner that adjustment may be made.

These and further advantages will appear from the following description taken in connection with the drawings.

Referring to the drawings:

Figure 1 is a front elevation of the door showing its manner of mounting in the passageway in the wall of a building.

Figure 2 is a vertical section through the door and part of the wall of a building.

Figure 3 is an enlarged front view of the left-hand lower corner of the door shown in Figure 1.

Figure 4 is a section on the line 4—4 of Figure 3.

Figure 5 is an enlarged view showing the central bracket member found in the lower end of the door as shown in Figure 1.

Figure 6 is a vertical section through part of the door panel, showing the bracket shown in Figure 5 but at right angles thereto.

Figure 7 is an enlarged section on the line 7—7 of Figure 1.

Figure 8 is a longitudinal section on the line 8—8 of Figure 7.

Figure 9 is a section on the line 9—9 of Figure 8.

Figure 10 is a section on the line 10—10 of 60 Figure 7.

Figure 11 is a section through one of the rollers showing its manner of mounting on the shaft of one of the hinges.

Figure 12 is a section through a guide member 65 showing a roller mounted therein.

This mechanism is adapted to be used in connection with garages, repair shops and other similar places, and is supported by the wall 1 of a building. In this building there is a doorway 2, which is to be closed by means of a vertical door which is adapted to be moved upwardly and to assume a horizontal position above the doorway during the time that the doorway is being used.

In this operation of the door the door is supported on each side by means of a guide member. The vertical part of this guide member is indicated by the numeral 3, the curved part by the numeral 4 and the horizontal overhead 75 part by the numeral 5. All of these parts together constitute a single guide member forming a continuous runway in which the rollers move. Attached to the wall of the building adjacent the upper side of the doorway is a 80 bracket 6. There is one of these brackets on each side of the door, and it is attached to the wall by any suitable means. At the lower end of the bracket there is a downwardly inclined slot 7 which terminates in a substantially vertical pocket 7a.

The door used for closing the doorway is formed of a large number of panels 8. In the present instance there are four of these panels shown, one pivoted to the other to form the 95 complete door. These panels are connected to one another by means of hinges 9. On each side of the upper section or panel there is attached to the door a bracket 10. This bracket may be attached to the door by means of bolts 100 or screws. Extending from the lower end of the bracket is an arm 11 which has on the outer end thereof a roller 12 for engagement with the lower part of the bracket 6 and within the slot 7 and seat 7a when the door is being closed 105 and is closed.

On the upper end of the bracket 10 there is pivotally mounted an arm 13. This arm is pivoted to the bracket 10 at one end and has on the other end thereof a roller 14. This roller 110

14 fits and moves along the guide members in the process of opening and closing the door. Extending from each of the hinges 9 is an extension shaft 15, which has on the outer end 5 thereof a roller 16 which is located within the guide member for the purpose of supporting the door and its panels, and for the purpose of guiding the parts of the door during the process of opening and closing. When the door is closed 10 these rollers are in the vertical part of the guide member. As the door is opened they shift from one part of the guide member to another until they finally assume positions in the horizontal part of the guide member. In this position the 15 door is fully open and supported overhead.

For the purpose of assisting in opening and closing the door there is provided a spring 17, as indicated in Figure 1. This spring, which 20 serves as a counterweight, is attached at one end 18 to a suitable part of the wall just above the doorway and to one side thereof. At the other end of the spring are two pulleys 19. Adjacent the point 18 where the spring is attached to the wall there is located on the wall a pulley 25 19a. On the wall across the doorway from the pulley 19 are two pulleys 20 and 21, located and supported on a plate 23 suitably attached to some part of the wall or to one of the bracket members 6.

Attached to the lower end at one side of the door is a cable or rope 22. This cable extends upwardly from the righthand lower corner of the door, as shown in Figure 1, over pulley 20 and around one of the pulleys 19 to a screw eye 21a, by which it is adjustably attached to the wall adjacent the pulleys 20 and 21. Attached to the lower lefthand corner of the door is one end of a second rope or cable 22a, which passes up over pulley 19a, around pulley 21 and around 40 the other pulley 19 to a screw eye 20a, by which the other end of the rope or cable is adjustably attached to the wall adjacent the pulleys 20 and 21. The tension of the spring tends to draw the door up and assist in opening it. When the 45 door is fully opened the pulleys 19 are nearer to the pulley 19a than they are as shown in Figure 1. By this arrangement of pulleys, springs and rope there is provided a compact, conveniently located counterbalance spring operated mechanism for assisting in opening the door.

In order to facilitate the movement of the door and provide means for grasping it by the hand there is a loop 24. There may be as many 55 of these loops as are necessary. This loop may be used for both opening and closing the door. In order to further assist in opening the door there may be provided a tread member 25 located on the extreme lower edge of the door. 60 For the purpose of securing the door in locked position there is provided, as shown in Figure 1, a lock 26. This lock is placed on one side of one of the panels and has a plunger adapted to fit through a hole in the wall of one of the guide members. While there is only one lock member shown there may be any number used. A chain 65 27 is used for raising and lowering the door.

Each hinge 9 is composed of two leaves 28 and 29. Each leaf 28 has on one end thereof 70 a pair of spaced ears 30, while each leaf 29 has on one end thereof a pair of ears 31. Each of these ears has a hole extending therethrough in which the shaft 15 fits. This shaft operates to hold the leaves together to form a complete 75 hinge. In order to prevent longitudinal move-

ment of the shaft 15 in the ears there is provided a cotter pin 32. Any other suitable means could be used for preventing longitudinal movement of this shaft. The shaft extends outwardly from the hinge members and has a reduced end 33, on which the roller 16 rotates. Each hinge is constructed and operates alike so the following description, while it applies to one particular hinge, applies equally to all the hinges used in connection with this door.

On the reduced part of the shaft 15 is a bearing ring 34. This bearing ring is mounted upon the part 33 so that it may or may not rotate therewith but will have a sliding movement along the reduced part. On the outer end of the shaft is a pin 36, which prevents the bearing ring 34 from running off the shaft. This bearing ring 34 has a raceway therein.

The roller 16 has in the center thereof a relatively large opening which has a flange 37 at one side of the roller. Within this opening and abutting against the flange is an annular bearing ring 38, which cooperates with the bearing ring 34 to form a ball race in which balls 39 are located for anti-friction purposes. 100 In order to hold the bearing ring 38 properly positioned in relation to the roller 16 there is provided an annular plate 40, which fits in a recess in one side of the roller and engages both of the bearing rings so that they are firmly held in position with relation to each other and with relation to the body of the roller. By this means the roller may easily rotate around the shaft and the bearing ring 34, and move longitudinally of the shaft with the bearing ring 110 34 but cannot move longitudinally of the shaft without the bearing ring 38. By this means there is permitted a slight sidewise movement of the door or one part of the door with respect to another part without jamming or pinching. 115 This free movement of the roller on the shaft also permits a slight variation in the guide member without pinching or binding.

For the purpose of strengthening the door and preventing its sagging, as when in an overhead, suspended condition, there is provided a transverse reinforcing bar 41. This bar is U-shaped and is attached at each end by means of eye members to the lower leaves of the hinges, or to other suitable plate members. One eye 125 member 42 is permanently anchored to one side of the door to either a lower leaf of a hinge or to a separate plate member, such as that shown in the lower righthand corner of the door. This eye member is attached to the door by means 130 of bolts and nuts 43. In one end of the eye member is a suitable hole or opening.

For the purpose of uniting one end of the reinforcing bar to the eye member there is a hole through the side walls of the transverse 135 supporting bar in line with the holes in the eye member. The edges of these holes are bent in, as indicated by the numeral 44, and closely grip around the inside of the hole in the eye and form for the eye a bearing closely fitting 140 and almost entirely surrounding the inner surface of the eye.

In order to securely hold these parts in the position shown in Figure 10 a suitable bolt 45 is provided. This bolt has the usual head and 145 nut. Adjacent the head and the nut are washers 46, the cooperating faces of which are concave in shape and adapted to closely engage the turned-in parts of the transverse bar around the holes therein so that though pressure be ap- 150

plied to the eye members the walls around the holes in the sides of the U-shaped transverse reenforcing member will not be straightened out but will be firmly held in position, owing 5 to the peculiar shape of the washers. Each end of the transverse reenforcing bar is provided with a similar means by which the eye members are attached thereto. However, the eye member on the lefthand side of the door, as shown in 10 Figure 3, instead of being anchored or fastened permanently to the edge of the door is fastened to a plate or hinge member by means of a screw and nut member 47. By this means the reenforcing bar may be tightened and held firmly 15 against the door to prevent the sagging thereof.

In Figures 3 and 10 the eye members are shown attached to plates located in the lower corners of the door. Plate 48, shown in Figure 10, is located in the lower righthand corner of 20 the door, while plate 49 is attached to the lower lefthand corner of the door. These plates in the present locations take the place of the lower leaves of the hinges for supporting the eye members, because in the present location there are 25 no hinges. From these plates also extend shafts 15, which have on the ends thereof the rollers 16, such as shown in Figure 11. In all places except the ends of the door the transverse reenforcing bar is attached at each end to the 30 lower leaf of a hinge, as clearly shown in Figure 1.

In order to support the intermediate part of the transverse reenforcing bar there is provided at each end of the door a U-shaped bracket member 50. This member fits over the intermediate part of the bar and prevents its sagging, and also holds it in close contact with the door. The other transverse reenforcing members are supported intermediate their ends by 40 U-shaped loops 51 in the lower leaf of an intermediate hinge. There is also provided a bracket member 52 attached to the door intermediate the ends of the reenforcing bar for projecting into the channel part of the U-shaped 45 member. This internal bracket 52 may be used alone or it may be used in connection with the brackets 50 and the loops 51 of the hinges. This bracket within the U-shaped transverse bar tends to preserve the shape of the transverse 50 bar and prevent any wobbling or unnecessary vibration thereof.

In the position shown in Figure 1 the door is in a closed condition. In order to open the door the hand loop 24 is seized, the door is lifted up 55 and caused to follow the guide or trackway 5. In this operation the operator is assisted by means of the spring 17, which tends to elevate the door. After the door has assumed a horizontal position the transverse reenforcing bars 60 prevent the central part of the door from sagging. In case the transverse bars should become loose they may be tightened by means of the nuts 47 on the ends of the adjustable eyes, and in order to facilitate and make easy the 65 operation of the door and to diminish the tendency to pinch or bind, the rollers on the ends of the shaft are loosely mounted so that there may be a certain amount of lateral movement of the rollers in relation to the door.

All of the parts of this door are separate and 70 distinct from the others and may be easily replaced when they become worn or broken.

I desire to comprehend within my invention 75 such modifications as may be clearly embraced within my claims and the scope of my invention.

Having thus fully described my invention, what I claim is new and desire to secure by Letters Patent, is:

1. In an overhead door, means for supporting the door, a reenforcing bar for said door, means for pivotally anchoring one end of said bar to the door, and means for adjustably attaching the other end of said bar to the door. 80

2. In an overhead door formed of sections united to one another by hinges, a reenforcing bar for said door, means to anchor one end of the bar to a hinge, and adjustable means for attaching the other end of said bar to another hinge. 85

3. In an overhead door formed of sections hinged to one another, a reenforcing bar for each section, a plate at each end of the bar, a roller supported by each plate, means for anchoring one end of said bar to one plate, and means for adjustably connecting the other end 90 of the bar to the other plate.

4. In an overhead door formed of pivotally connected sections in combination with guide means, a plate at each side of each section, anti-friction means supported by each plate engaging 100 the guide means, and a reenforcing bar pivotally attached to one plate and adjustably attached to the other plate.

5. In an overhead door formed of sections united to one another by leaf hinges, a U- 105 shaped reenforcing bar extending across certain of the sections with each end attached to one leaf of a hinge, and one leaf of another hinge bent into a U-shaped bracket to fit over the reenforcing bar and support an intermediate 110 part thereof.

6. In an overhead door formed of sections united to one another by leaf hinges, in combination with guideways, a roller attached to each hinge to engage the guideways for guiding 115 and supporting the door, a reenforcing bar for each section anchored at one end to a leaf of a hinge and adjustably attached at its other end to a leaf of another hinge.

7. In an overhead door, in combination with 120 a pair of guides, a pair of door sections, a pair of leaf hinges uniting the adjacent ends of the sections, each hinge having a shaft with a roller engaging a guide, a reenforcing bar attached to a leaf of each hinge and extending across the 125 door, and another leaf hinge uniting the sections and forming a support for the reenforcing bar and an additional leaf hinge uniting the sections and forming the support for the reinforcing bar. 130

8. In an overhead door, in combination with a pair of guide members, leaf hinges uniting the adjacent ends of the sections, each hinge having a shaft with a roller engaging a guide member, and a reenforcing bar anchored at one end to a leaf of one hinge and adjustably attached at 135 its other end to a leaf of the other hinge.

9. In an overhead door, in combination with a pair of guide members, a leaf hinge uniting each pair of adjacent ends of the sections, and 140 a third leaf hinge uniting the intermediate parts of the sections, each end hinge having a shaft with a roller engaging a guide member, and a reenforcing bar attached at each end to a leaf 145 of a hinge and the third hinge having a leaf looped over the intermediate part of the bar to hold the bar and the door together.

10. In an overhead door, in combination with a pair of guide members, a leaf hinge uniting each pair of adjacent ends of the sections and 150

- a third hinge uniting the intermediate parts of the sections, each end hinge having a shaft with a roller engaging a guide member, and a reenforcing bar anchored at one end to a leaf of one end hinge and adjustably attached at its other end to a leaf of the other end hinge and having a leaf of the third hinge looped over the intermediate part thereof to hold the bar and the door together. 80
- 10 11. In an overhead door, in combination with a pair of guide members, a plate attached to each side of the door, a shaft on each plate, a roller mounted on each shaft for longitudinal movement thereon and engaging a guide and a reenforcing bar pivotally attached to one plate and adjustably attached to the other plate adapted to keep the door from sagging. 85
- 15 12. In a door, an eye member attached to each side of the door, and a U-shaped reenforcing bar, each end of the bar fitting over an eye member and having therethrough a hole in line with the eye and the material around the hole pressed into the eye to serve as a bearing for the eye. 90
- 20 13. In a door, an eye member attached to each side of the door, a U-shaped metal reenforcing bar, each end of the bar fitting over an eye member and having therethrough a hole in line with the eye and the metal around the hole pressed into the eye, and a bolt to hold the U-shaped member in engagement with the eye. 100
- 25 14. In a door, an eye member attached to each side of the door, a U-shaped metal reenforcing bar, each end of the bar fitting over an eye member and having therethrough a hole in line with the eye and the metal around the hole pressed into the eye, and a bolt passing through the hole and eye having cone-shaped parts to engage the pressed-in parts of the bar to hold the eye to the bar. 105
- 30 15. In combination, a door, an anchor mounted thereon, a plate connected to said anchor adapted to engage the face of the door continuously throughout the width thereof, and an adjusting means on the other side of the door from the anchor connected to said plate to draw the plate against the face of the door. 110
- 35 16. In combination, a door, an anchor mounted thereon, a plate connected to said anchor adapted to engage the face of the door continuously throughout the width thereof, an adjusting means on the other side of the door from the anchor connected to said plate to draw the plate against the face of the door, said plate having a pair of spaced bearing faces engaging said door and said anchor, and adjusting means being connected to said plate in spaced relationship from the face of the door, whereby said bearing faces are caused to press against the face of the door to maintain it in alignment, an intermediate clamping member mounted on said door and encircling said plate to prevent its intermediate movement away from the center of the door, hinge members connected to said anchor, intermediate plate and adjusting means for hinging to the door another section thereof. 115
- 40 17. In combination, a door, an anchor mounted thereon, a plate connected to said anchor adapted to engage the face of the door continuously throughout the width thereof, an adjusting means on the other side of the door from the anchor connected to said plate to draw the plate against the face of the door, said plate having a pair of spaced bearing faces engaging said door and said anchor, and adjusting means being connected to said plate in spaced relationship from the face of the door, whereby said bearing faces are caused to press against the face of the door to maintain it in alignment. 120
- 45 18. In combination, a door, an anchor mounted thereon, a plate connected to said anchor adapted to engage the face of the door continuously throughout the width thereof, an adjusting means on the other side of the door from the anchor connected to said plate to draw the plate against the face of the door, said plate having a pair of spaced bearing faces engaging said door and said anchor, and adjusting means being connected to said plate in spaced relationship from the face of the door, whereby said bearing faces are caused to press against the face of the door to maintain it in alignment, an intermediate clamping member mounted on said door and encircling said plate to prevent its intermediate movement away from the center of the door, hinge members connected to said anchor, intermediate plate and adjusting means for hinging to the door another section thereof. 125
- 50 19. In combination, a door, an anchor mounted thereon, a plate connected to said anchor adapted to engage the face of the door continuously throughout the width thereof, an adjusting means on the other side of the door from the anchor connected to said plate to draw the plate against the face of the door, said plate having a pair of spaced bearing faces engaging said door and said anchor, and adjusting means being connected to said plate in spaced relationship from the face of the door, whereby said bearing faces are caused to press against the face of the door to maintain it in alignment, an intermediate clamping member mounted on said door and encircling said plate to prevent its intermediate movement away from the center of the door, hinge members connected to said anchor, intermediate plate and adjusting means for hinging to the door another section thereof, and pivot members for said hinges forming the anchor and adjusting means extending beyond the sides of the door, and slideable rollers mounted on said pivots beyond the margins of said door. 130
- 55 60 65 70 75 80 85 90 95 100 105 110 115 120 125 130 135 140 145 150

EDWARD H. McCLOUD. 135
